United States Patent Office

Des. 177,701
Patented May 15, 1956

177,701

ELECTRIC AIR COMPRESSOR

Robert E. Sykes, Evanston, Ill., assignor to Bell & Gossett
Company, Morton Grove, Ill., a corporation of Illinois

Application December 8, 1954, Serial No. 33,451

Term of patent 14 years

(Cl. D65—1)

The figure is a perspective view taken from the front end and one side of an electric air compressor embodying my new design, the opposite end being substantially plain and the other side being like the side shown.

I claim:

The ornamental design for an electric air compressor, as shown and described.
